United States Patent Office

Des. 211,383
Patented June 11, 1968

211,383

PITCHER

Victor F. Anderson, 13 W. Mantua Ave.,
Wenonah, N.J. 08090

Filed Sept. 21, 1967, Ser. No. 8,708

Term of patent 14 years

(Cl. D44—21)

FIG. 1

FIG. 2

FIG. 3

FIG. 4

FIG. 5

I claim:

The ornamental design for a pitcher, as shown.
